EAR STOPPER

Vern O. Knudsen, Los Angeles, Calif.

Application August 13, 1938, Serial No. 224,759

12 Claims. (Cl. 128—152)

This invention relates to ear stoppers and relates more particularly to ear protectors or ear stoppers for use by those who are disturbed by noises and undesirable sounds, by those who are subjected to the detonations and excessive air disturbances of gun fire, riveting, blasting, etc., and by swimmers or others who wish to keep water or other undesirable substances from entering the ear canal.

Another object of this invention is to provide ear stoppers embodying combinations or series of acoustical elements related and designated to provide a substantial sound transmission loss or insulation throughout a wide range of audible frequencies. In accordance with my invention the networks or series of acoustical elements of the stoppers may be so chosen and related as to provide a sound transmission loss or sound insulation characteristic comparable with that provided by the temporal bone and other anatomical structures that surround and embed the human internal ear or cochlea.

Another object of this invention is to provide ear stoppers that embody series of acoustical elements or impedances coupled by other acoustical impedances to constitute acoustical networks or combinations that provide the required or desired ratio between the transmitted and the incident sound energy throughout a given frequency range.

Another object of this invention is to provide ear protectors or ear stoppers of the character mentioned that embody series or pluralities of acoustical impedances in the nature of mass or inertia elements coupled by compliance type impedance elements in the form of loose couplings between the "mass" impedances which transmit a minimum of sound energy between the "mass" impedances.

Another object of this invention is to provide ear stoppers of the character mentioned in which the "mass" impedances are in the form of parts of similar or dissimilar materials having different sound transmission coefficients, and the compliance impedances are in the nature of yielding walls or separators enclosing or defining spaces, voids or gas chambers between the "mass" impedances.

Another object of this invention is to provide ear stoppers of the character mentioned that are simple and inexpensive to manufacture.

A further object of this invention is to provide ear stoppers of the character referred to that are convenient and comfortable to use, that are non-toxic and that are very durable.

The various objects and features of my invention will be fully understood from the following detailed description of typical preferred forms and applications of the invention, throughout which description reference is made to the accompanying drawing, in which:

Fig. 1 is a side elevation of one form of stopper of the invention showing it in position in the auditory canal. Fig. 2 is an enlarged longitudinal detailed sectional view of the stopper illustrated in Fig. 1. Fig. 3 is a view similar to Fig. 2 illustrating another form of the invention, and Fig. 4 is a reduced longitudinal sectional view of still another form of the invention.

In the following detailed description I will describe three typical preferred forms of the invention. It is to be understood that the invention may be varied considerably without departing from its broader principles and the invention is not to be construed as limited or restricted to the specific forms about to be described.

The ear stopper of the present invention illustrated in Figs. 1 and 2 of the drawing may be said to comprise, generally, a yielding body 10 for insertion in the auditory canal C, a plug 11 in the outer portion of the body 10 constituting an impedance of the mass type and a plug or mass 12 in the inner portion of the body 10 forming a second mass impedance spaced from the plug 11.

The body 10 of the device or stopper is designed to be inserted in the meatus or auditory canal C of the human ear. The body 10 is an elongate tubular or hollow member preferably of sufficient diameter to snugly fit the canal C. In accordance with the invention the body 10 is formed of a flexible, yielding and resilient material such as rubber, rubber composition, rubber substitute, or the like. The outer end of the body 10 is open to receive the plug 11 and the inner end of the body 10 may be closed, as illustrated in the drawing.

It is preferred to make the inner end of the body 10 round or convex in external configuration to facilitate the introduction of the stopper to the auditory canal C. In the construction illustrated the body 10 has a partially spherical enlargement 13 on its inner end to present the desirable rounded or convex surface to facilitate a snug fit and complete closure of the auditory canal C and to assist in retaining the stopper in place. As will be subsequently described the body enlargement 13 may be provided or formed by the "mass" 12 within the body. This "mass" 12 may be made of the same material as the body 10, or of dissimilar material; and other shapes may be de-

50
45
55

sirable to provide the best possible fit in the ear canal.

The plug 11 constitutes the first or outer inertia "mass" acoustical impedance element of the device, being located in the outer portion of the body 10 to receive the incident sound energy. The plug 11 is preferably a solid or non-hollow member of brass, stainless steel, lead, bronze or similar metal or material of relatively high specific gravity. In practice the plug 11 may be tapered as shown to impart a similar taper to the body 10. The major portion of the plug 11 is inserted in the outer part of the body 10 and is suitably secured in the body. The plug 11 may be cemented, vulcanized or otherwise fixed in the stopper body 10. The plug 11 may extend outwardly beyond the end of the body 10, or it may be partially or completely surrounded by the body 10 in such a manner as to add to the comfort of wearing the device and to facilitate the insertion and removal of the stopper. In the particular embodiment of the invention shown in Figs. 1 and 2 the projecting portion of the plug 11 is enlarged in diameter and is shaped to constitute a handle or knob 14 that may be conveniently engaged for the purpose of inserting the stopper in the auditory canal C and for the purpose of withdrawing the stopper from the ear. If desired or believed necessary the knob 14 may be covered with a skin or coating 15 of rubber, or the like, or as shown in Fig. 3, the wall of the body 10 may diverge or flare outwardly and partially surround the knob 14 and thus prevent the plug 11 from touching the ear. Such diverging wall or flange may also improve the fit of the stopper in the ear canal and may also facilitate easy removal of the stopper. The inner end of the plug 11 is preferably spaced a considerable distance from the inner enlargement 13 of the stopper body 10, but limitation of space in the ear canal may require a short distance.

The plug or mass 12 constitutes the second or inner mass or inertia type of acoustical impedance of the stopper. The mass 12 is provided in the inner part of the body 10 and in the structure illustrated occupies the hollow enlargement 13 of the body. The shape and proportions of the mass 12 may be such that the mass distends the yielding resilient body 10 to provide and maintain the enlargement 13, or if desired the body enlargement 13 may be preshaped or preformed to receive the mass 12, or the mass 12 may be cast or formed of the same material as is used for the body 10 in such shape as will best fit the ear canal. The parts may be related and proportioned so that the inherent resiliency of the body 10 holds the mass 12 in its proper position. If desired or believed necessary the mass 12 may be cemented, vulcanized or otherwise secured in place in the body 10. It is preferred to construct the mass 12 of a yielding material such as soft rubber, sponge rubber, beeswax, or the like, so that it will not cause injury to the ear when the stopper is inserted in the auditory canal C. Owing to the fact that the mass 12 is of soft or yielding material its acoustical compliance and resistance may be substantial although the mass 12 is primarily a mass impedance.

In accordance with the invention the mass 12 is spaced from the inner end of the plug 11 to leave or provide a space or chamber 16 in the body 10. In practice the chamber 16 may be of substantial longitudinal extent as illustrated in the drawing. As will be evident the chamber 16 is defined or enclosed by the surrounding wall 75

of the body 10 and the opposing end surfaces of the plug 11 and the mass 12. The chamber 16 may contain air or other gas or, if desired, a partial vacuum may be maintained in the chamber 16. In the event that the chamber 16 contains a gas or in the event that a partial vacuum is maintained in the chamber the plug 11 is sealed in the body 10.

In the use or operation of the stopper illustrated in Figs. 1 and 2 of the drawing the stopper is inserted in the auditory canal C to occupy a position such as illustrated in Fig. 1. If desired the body 10 may be provided or covered with petroleum jelly, or the like, prior to the insertion of the stopper so that the stopper may readily enter the canal C. The stopper may be allowed to remain in the ear for as long a period as required and may be removed when desired.

The stopper is highly efficient in its sound insulation properties. The dense metal plug 11 forms the outer acoustical impedance or mass impedance of the device. The plug 11, being of dense material, has a small acceleration or displacement imparted to it by the force of the incident sound waves or explosion waves in the case of gun fire, blasting, etc. The mass 12 constitutes a second inertia or mass acoustical impedance but being of soft material may have an appreciable acoustical compliance and resistance. The wall 30 of the yielding body 10 and the chamber 16 between the plug 11 and the mass 12 constitute a very loose coupling between the plug and mass 12. This loose coupling is a highly efficient acoustical compliance and resistance element and only a small fraction of sound energy communicated to the plug 11 is transmitted by the said loose coupling to the mass 12. From the above it will be apparent that the stopper of the invention shown in Figs. 1 and 2 involves two mass impedances separated by a flexible coupling. By variation of the mass and size of the plug 11, the character of the gas in the chamber 16, the dimensions of the chamber 16, the thickness and compliance of the wall of the body 10 and the size, compliance and density of the mass 12, the sound transmission and insulating characteristics of the device or stopper may be altered to suit various conditions of use or application. The stopper constructed as described above provides a transmission loss or sound insulation of between approximately 45 to 60 decibels throughout a wide range of audible frequencies.

The form of the invention illustrated in Fig. 3 of the drawing is characterized by an additional or third mass impedance. The improved ear stopper of the invention illustrated in Fig. 3 may be said to comprise, generally, a body 10^a, a plug 11^a in the outer portion of the body 10^a, a mass 12^a in the inner portion of the body 10^a and a partition 18 in the body 10 spaced between the plug 11^a and the mass 12^a.

The body 10^a may be similar to or identical with the body 10 described above and the plug 11^a may be similar to the plug 11. In the particular case illustrated the plug 11^a is somewhat shorter than the plug 11 and has a smaller knob 14^a. The body 10^a may have a flaring flange or skirt 30 extending outwardly beyond the knob 14^a. The skirt prevents contact of the knob 14^a with the user, limits insertion of the stopper in the auditory canal, assures a better fit of the stopper in the canal and facilitates the removal of the stopper from the ear. The mass 12^a is similar to the above described mass 12 and occupies the enlarged inner portion 13^a of the body 10^a. The

mass 12^a is preferably formed of soft or yielding material and is provided with a central cavity 19 to render it more yielding. The body 10^a, the plug 11^a and the mass 12^a may be constructed of the same materials as the body 10, plug 11 and mass 12, respectively, of the previously described form of the invention. Furthermore, such features as characterize the device illustrated in Fig. 3, as the cavity or hollow of the mass 12^a, may also characterize the device illustrated in Figs. 1 and 2.

The partition 18 constitutes the third acoustical impedance of the stopper. The partition 18 is arranged transversely across the interior of the body 10^a at a point between the plug 11^a and the mass 12^a to partition the interior of the body into two chambers 20 and 21. In practice the partition 18 may be substantially equally spaced between the opposing ends of the plug 11^a and the mass 12^a although the position of the partition may be varied as found desirable. The partition 18 may be constructed of any suitable material having a substantial density. Any suitable means may be employed to retain the partition 18 in the body 10^a. In the typical arrangement illustrated the edge or peripheral portion of the partition is gripped or received in an internal groove 22 in the wall of the body 10^a. If desired or necessary the partition 18 may be cemented or vulcanized in the groove 22.

The two chambers 20 and 21 in the body 10^a may contain air or gas, or a partial vacuum may be maintained in the chambers. Cotton or wool fibre F, synthetic fibre, or the like, is loosely arranged in the chambers 20 and 21 to provide a better sound insulation.

The stopper of the invention illustrated in Fig. 3 may be employed in the same manner as the previously described form of the invention. The stopper shown in Fig. 3 operates in substantially the same manner as the previously described form of the invention; however, it embodies a third mass acoustical impedance, namely, the partition 18. It will be seen that the stopper of Fig. 3 embodies three inertia or mass impedances coupled by loose couplings. The three mass impedances are found in the plug 11^a, the partition 18 and the mass 12^a and the loose couplings are found in the body wall and the chambers 20 and 21 between the spaced impedances. The loose couplings between the series of spaced mass impedances transmit a minimum of the sound energy from one mass impedance to the other and the network or system constitutes a highly efficient sound insulation device.

Fig. 4 of the drawing illustrates a form of the invention particularly adapted for use by swimmers and others who wish to prevent the entrance of fluids to the ears. In this form of the invention the body 10^b is longitudinally tapered and is provided at its outer end with a flaring flange or skirt 30^b similar to the above described skirt 30. The body 10^b may be constructed of rubber, rubber composition, or the like, and is flexible and resilient. The inner acoustical impedance mass 12^b is formed integral with the body 10^b. As shown in the drawing the mass 12^b may take the form of an internal enlargement in the inner portion of the stopper body 10^b. The outer acoustical impedance mass or plug 11^b is in the form of a separator or partition extending transversely across the interior of the body 10^b. The plug 11^b may be constructed of any suitable material, for example, it may be formed of the same material as the above described mass 11. 70

5 The plug 11^b is spaced some distance forwardly from the mass 12^b, providing a chamber 16^b within the body 10^b. Any suitable means may be employed to secure the plug 11^b in place. In the case illustrated the peripheral portion of the plug 11^b is received and secured in an internal groove 22^b in the body 10^b.

10 Having described only typical preferred forms and applications of my invention, I do not wish to be limited or restricted to the specific details herein set forth, but wish to reserve to myself any variations or modifications that may appear to those skilled in the art, or which fall within the scope of the following claims:

15 Having described my invention, I claim:

1. An ear stopper of the character described comprising spaced solid matter parts forming acoustical mass impedances, said parts being of different densities, and a yielding tubular body adapted to be received in the auditory canal whose end portions contain and are defined by the solid matter parts, the body constituting an acoustical compliance coupling said parts.

2. An ear stopper of the character described comprising spaced solid matter parts forming acoustical mass impedances, one of said parts

20 being of dense unyielding material and the other part being of less dense yielding material, and a hollow yielding body adapted to be received in the auditory canal and whose end portions contain and are defined by said parts, the body together with said parts defining a closed chamber, said body and chamber constituting a loose compliance coupling between said parts.

3. An ear stopper including a series of spaced masses having different sound transmission coefficients constituting acoustical inertia impedances, and a yieldable tubular body extending between and connecting said masses and constituting an acoustical compliance impedance coupling, said masses and the body defining closed chambers between the masses.

4. An ear stopper including a series of spaced masses having different sound transmission coefficients constituting acoustical inertia impedances, and a tubular body of yielding material carrying and connecting said masses and defining chambers between the masses, the body and said chambers forming acoustical compliance impedance couplings between the masses.

5. An ear stopper comprising an elongate hollow yieldable body adapted to be inserted in the auditory canal, a yieldable solid matter mass closing the inner end of the body and a substantially unyielding solid matter mass closing the outer end of the body and maintaining the shape of the outer portion of the body, the last named mass being spaced from the yieldable mass to leave a closed chamber in the body.

6. An ear stopper comprising an elongate hollow body of yieldable resilient material, a plug of dense solid matter material confined in one end portion of the body by the resiliency of the body, and a mass of soft solid matter material confined in the other end portion of the body in spaced relation to said plug to leave a closed space in the body.

7. An ear stopper comprising a tubular yieldable body closed at its inner end and adapted to be introduced into the auditory canal, a metal plug in the outer portion of the body, and a soft mass in the inner portion of the body spaced from the plug, said plug and mass being spaced apart to leave a closed chamber in the body.

8. An ear stopper comprising a tubular yield-

able body closed at its inner end and adapted to be introduced into the auditory canal, a mass in the inner portion of the body, and a mass sealed in the outer portion of the body, one of said masses being soft and the other being of substantial density, said masses being spaced apart to provide a closed chamber in the body.

9. An ear stopper comprising a tubular yieldable body to be inserted in the auditory canal, acoustical inertia impedance masses in the opposite end portions of the body, and a partition spaced between said masses and extending across the interior of the body.

10. An ear stopper comprising a tubular yieldable body to be inserted in the auditory canal, a dense plug in one end portion of the body, a mass in the other end portion of the body, and a transverse partition in the body spaced from

the plug and mass to leave chambers in the body.

11. An ear stopper comprising a tubular yieldable body to be inserted in the auditory canal, a dense plug in one end of the body, a yieldable mass in the other end of the body, a transverse partition in the body spaced from the plug and mass to leave chambers in the body, and absorptive fibre in said chambers.

10 12. An ear stopper comprising a tubular yieldable body closed at its inner end and adapted to be introduced into the auditory canal, a flaring skirt on the outer end of the body, a metal plug in the outer portion of the body, and a soft mass in the inner portion of the body spaced from the plug.

VERN O. KNUDSEN.
